Primary Examiner—Caron Veynar*Assistant Examiner*—Sydney R Buffalow(74) Attorney, Agent, or Firm—H. Frederick Rusche; Husch Blackwell Sanders LLP(57) CLAIM

I claim the ornamental design for a shoe rack, as shown and described.

DESCRIPTION

FIG. 1 is a perspective view of a shoe rack showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIG. 8 is a left side view of a shoe rack in an alternate position thereof; and,

FIG. 9 is a perspective view of a shoe rack in a second embodiment.
